UNITED STATES PATENT OFFICE.

FERDINAND J. TILLMAN, OF ST. LOUIS, MISSOURI, ASSIGNOR TO YARD-O-METER CORPORATION, OF ST. LOUIS, MISSOURI, A CORPORATION OF MISSOURI.

DESIGN FOR A CASING FOR A CLOTH-MEASURING MACHINE.

Application filed February 10, 1922. Serial No. 639. Term of patent 14 years.

To all whom it may concern:

Be it known that I, FERDINAND J. TILLMAN, a citizen of the United States, residing at St. Louis, and State of Missouri, have invented a new, original, and ornamental Design for a Casing for a Cloth-Measuring Machine, of which the following is a specification, reference being had to the accompanying drawing, forming part thereof.

Figure 1 is a perspective view of the casing showing my new design.

Figure 2, is a perspective view of the reverse side of Fig. 1.

I claim:

The ornamental design for a casing for a cloth measuring machine, as shown.

FERDINAND J. TILLMAN.
